Primary Examiner — Barbara Fox*Assistant Examiner* — Lilyana Bekic(74) *Attorney, Agent, or Firm* — Merchant & Gould P.C.(57) **CLAIM**

The ornamental design for an inhaler base plate with mouthpiece, as shown and described.

DESCRIPTION

FIG. 1 is a front, top, left side perspective view of an inhaler base plate with mouthpiece in accordance with the new design;

FIG. 2 is a rear, top, right side perspective view thereof; FIG. 3 is another front, top, left side perspective view thereof;

FIG. 4 is a right side view thereof;

FIG. 5 is a top view thereof; and,

FIG. 6 is a bottom view thereof.

The portions shown in broken lines form no part of the claimed design.
